UNITED STATES PATENT OFFICE.

CLYDE H. GOUDELOCK, OF CHARLOTTE, NORTH CAROLINA.

AUCTION-BRIDGE SCORE CALCULATOR.

Application filed January 25, 1924. Serial No. 688,514.

To all whom it may concern:

Be it known that I, CLYDE H. GOUDELOCK, a citizen of the United States of America, and a resident of Charlotte, county of Mecklenburg, and State of North Carolina, have invented certain new and useful Improvements in Auction-Bridge Score Calculators, of which the following is a full and clear specification.

10 The object of this invention is to provide a simple device whereby the total points won on any successful bid may be quickly indicated, as more fully hereinafter set forth.

In the drawing—

15 Fig. 1 is a plan view of my device; Fig. 2 is a plan view of the base card or plate with the rotary indicator removed; Fig. 3 is an edge elevation of the device.

In the drawing, 5 designates a base-card 20 or disk, and 6 designates a smaller disk pivoted centrally on the main disk and provided at one point in its circumference with a pointer 7, adjacent to which is a radial slot 8. On the face of the smaller disk may be 25 printed a table giving the honor points, in accordance with the well-known method of counting honors.

30 Around the top disk, on the main disk, is printed a series of five trump groups of figures each running from 1 to 7 and each group being designated by the symbol 9 indicating a trump. These trump figures are all arranged adjacent the edge of the smaller disk, so that the smaller disk may be rotated 35 to bring its pointer 7 opposite any one of the trump figures.

Underneath the upper disk, upon the upper face of the main disk, are printed 40 five segmental groups of figures, each containing seven radial series of figures, one in

line with each of the trump numerals. Each of these segmental groups of figures indicates the score for a successful bid in that one of the trump groups with which it is associated. To indicate the value of a bid, 45 the central disk is rotated to bring its pointer to a point in juxtaposition to the marginal trump figure in the group in which the bid is made. As shown in Fig. 1, the top disk is adjusted for a bid of 6 clubs, and this adjustment brings to view the radial row of figures on the main disk which indicates the value of this bid, whether the bid be simple, doubled or redoubled, suitable indicia being placed along the top edge of the 50 slot 8 to designate the various values.

In the present drawing, the figures indicate the score in what is known as progressive auction bridge, but it will be understood that the figures may be adapted for the 55 ordinary or regular game of auction bridge without departing from the spirit of my invention.

What I claim is:

A base disk and a supplemental disk rotatively mounted thereon, the supplemental disk being provided with an edge pointer and with a radial slot adjacent thereto and the main disk being provided with a series of five groups of bid figures around the 60 margin of the supplemental disk, each of these groups being designated by a trump symbol, said main disk being also provided underneath the supplemental disk with five 65 groups of radially-arranged figures indicating the value of the tricks in the various trump suits.

In testimony whereof I hereunto affix my signature.

CLYDE H. GOUDELOCK.
